(57) **CLAIM**

The ornamental design for an evaporative cooling system water container, as shown and described.

DESCRIPTION

FIG. 1 is a top, front, and right side perspective view of an evaporative cooling system water container showing my new design, the broken-line disclosure being understood to represent portions of the article in which the claimed design is embodied, but which forms no part of the claimed design;

FIG. 2 is an enlarged top, front, and right side perspective view thereof;

FIG. 3 is an enlarged front elevational view thereof;

FIG. 4 is an enlarged right side elevational view thereof;

FIG. 5 is an enlarged left side elevational view thereof;

FIG. 6 is an enlarged top plan view thereof; and,

FIG. 7 is an enlarged bottom plan view thereof.
